UNITED STATES PATENT OFFICE

2,127,506

FURNACE

George William Franzheim, Dunkirk, N. Y.

Application November 13, 1936, Serial No. 110,767

4 Claims. (Cl. 110—29)

This invention relates to furnaces and more especially to down draft furnaces of that type shown for example in Patent 1,139,660 issued to me on May 18, 1915.

In furnaces such as the patented one, fuel is delivered onto the upper grate and sifts therefrom onto the lower grate where it is consumed, the gases and other hot products of combustion flowing outwardly from between the two grates into the water section of the furnace.

An object of the present invention provides a means for automatically feeding the fuel downwardly through the upper grate as needed, said means operating to agitate and break up the fuel supported on the grate so that said fuel can gravitate into the combustion chamber thereunder.

A further object is to provide fuel feeding means which can be thermostatically controlled whereby a furnace will be supplied with fuel in the combustion chamber or fire box as needed to maintain a predetermined temperature.

With the foregoing and other objects in view, which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

In the accompanying drawings the preferred forms of the invention have been shown.

In said drawings

Figure 1 is a view partly in section and partly in elevation of a down draft furnace equipped with the present invention.

Figure 2 is a front elevation.

Figure 3 is a section through a portion of the furnace taken on line 3—3, Figure 1.

Figure 4 is a view similar to Figure 1 showing another form of the invention.

Figure 5 is a front elevation thereof.

Figure 6 is a section through a portion of the furnace taken on line 6—6, Figure 4.

Figure 7 is a view similar to Figures 1 and 4 showing another modification.

Figure 8 is a front elevation thereof.

Figure 9 is a section through a portion of the furnace on line 9—9, Figure 7, a part of the furnace being shown in plan.

Referring to the figures by characters of reference 1 designates a boiler or other heat generating unit of the down draft type provided with a lower grate 2 and an upper grate 3, there

being a firebox or combustion chamber 4 between these grates which opens into the boiler section 5.

In practice a supply of fuel is fed to the upper grate 3 and is adapted to be sifted downwardly through the grate into the combustion chamber or fire box. An object of the present invention is to provide a means whereby the fuel can be broken up and fed downwardly through the upper grate as needed. One such means has been illustrated in Figures 1, 2 and 3 and includes parallel tubular shafts 6 located above but close to the grate 3. The out ends of these shafts are open so that fresh air may be supplied thereto, this air escaping into the furnace through vents 7 in the shaft. Agitating teeth or fingers extend from each shaft, as indicated at 8 and are adapted to work above and close to the spaces between the bars of the upper grate 3, as shown in Figure 1.

Secured to each tubular shaft is a gear 9 forming part of the speed reduction mechanism whereby motion is transmitted from a counter-shaft 10 and worms 11. This counter-shaft is driven by gears 12 from an electric motor 13. The motor can be controlled in its operation by a thermostat 14.

A supply of fuel is deposited on the upper grate and will of course cover the shafts 6 and the teeth or fingers thereon. Fuel on the lower grate 30 will be consumed within the fire box or combustion chamber 4 and the products of combustion will flow outwardly through the sections 5 as ordinarily. When it is necessary to supply additional fuel to the fire box, the motor 13 is operated and motion will be transmitted therefrom through the gearing 12 and the speed reduction mechanism to the shafts 6 which will be rotated slowly, causing the teeth or fingers 8 to plow through the fuel and break it up and at the same time cause it to sift between the bars of grate 3 and into the combustion chamber.

As the shafts 6 are open at their outer ends and have vents 7 in them, fresh air can flow through the shafts and into the fuel, this air operating to keep the shafts cool and the air serving to assist in the support of combustion in the fire box or chamber 4.

Instead of providing rotating tubular shafts above the upper grate, shafts 15 can be journaled in the wall of the furnace above the level of the upper grate 3 and these shafts can be formed with crank extensions 16 which are supported close to the grate 3 and constitute means for agitating fuel and causing it to sift between the 55

bars of the upper grate. These crank extensions 16 can be suitably journaled at those ends thereof within the furnace and as shown at 17 in Figure 4.

- 5 Any suitable means can be provided for causing the crank-like extensions to oscillate while in use. For example the outer ends of the shafts 15 can be formed with depending arms 18 all of which are connected at their lower ends to a transverse bar 19 mounted in guides 20 and 21. A spring 22 can be housed in the guide 20 for exerting a thrust against bar 19 to maintain it normally in an intermediate position with arms 18 substantially vertical. A pitman 23 connects the bar 19 to an operating crank 24 which is driven through gears 25 by a thermostatically controlled motor 26.

In this form of the invention the motor, when set in motion, will cause the bar 19 to reciprocate and the arms 18 to oscillate. Thus the crank extensions 16 will be oscillated within the fuel piled on the grate 3 with the result that this fuel will be broken up and caused to sift between the bars of the grate and into the combustion chamber 4.

20 A third form of the invention has been illustrated in Figures 7 to 9 inclusive. In this modified structure a shaft 27 is mounted for rotation and reciprocation within a guide 28 at the top 30 of the casing of the boiler. Connected to the bottom of the shaft close to and above the grate 3 is a skeleton wheel or agitator 29 having projecting teeth or fingers 30.

25 A stationary cam 31 is secured on the boiler and its upper or cam base engages the lower base of a cam 32 which is secured to and moved with the shaft 27. These cams are shown in elevation in Figure 8 and it will be noted by referring thereto that when the shaft is rotated 40 and cam 32 moves therewith, the said cam will ride upwardly upon the lower cam 31 and then gravitate to its lowermost position. Thus the shaft will be reciprocated as it rotates.

For the purpose of actuating the shaft there 45 is provided a worm wheel 33 feathered on shaft 27 but held against up and down movement by bearings 34 provided therefor. A screw 35 driven by the shaft of an electric motor 36 serves to rotate the wheel 33 at a reduced speed. This 50 motor can be thermostatically controlled as shown.

In practice fuel is placed on the upper grate 3 and will of course cover the agitating element 29. When the motor is started for the purpose 55 of supplying additional fuel, shaft 27 will be

rotated and reciprocated and a corresponding movement of the agitator 29 will be set up with the result that the fuel will be thoroughly agitated and will be caused to sift downwardly between the bars of grate 3 and into the fire box 4. 5

It is to be understood that various other modifications of this invention may be employed.

What is claimed is:

1. In a down draft furnace for boilers or the like the combination with a stationary upper 10 grate and a lower grate forming a combustion chamber therebetween, and a fuel space above the upper grate, of means within the fuel space close to and above the upper grate and positioned for agitating unburned fuel on the upper 15 grate for gravitation through said upper stationary grate into the combustion chamber, and means for automatically operating said agitating means.

2. The combination with a down draft furnace 20 having superposed grates providing a combustion chamber therebetween and fuel receiving space above the upper grate, of a shaft extending into said space, fuel agitating means carried by the shaft and supported adjacent to the upper 25 grate, a motor, and means operated by the motor for actuating the shaft to move the agitating means about the axis of said shaft, said agitating means including a crank extension extending from the shaft.

3. The combination with a down draft furnace 30 having superposed grates providing a combustion chamber therebetween and fuel receiving space above the upper grate, of a shaft extending into said space, fuel agitating means carried by the 35 shaft and supported adjacent to the upper grate, a motor, and means operated by the motor for actuating the shaft to move the agitating means about the axis of said shaft, said agitating means including a skeleton wheel and projections on the wheel.

4. The combination with a down draft furnace 45 having superposed grates providing a combustion chamber therebetween and fuel receiving space above the upper grate, of a shaft extending into said space, fuel agitating means carried by the shaft and supported adjacent to the upper 50 grate, a motor, and means operated by the motor for actuating the shaft to move the agitating means about the axis of said shaft, said shaft being tubular and opening outwardly through the casing, there being vents within the shaft for delivering air into the furnace.
